CLAIM

I claim the ornamental design for an ice shaver, as shown and described.

DESCRIPTION

FIG. 1 is a perspective view thereof;

FIG. 2 is a side view thereof;

FIG. 3 is an opposite side view thereof;

FIG. 4 is a front view thereof;

FIG. 5 is a rear view thereof;

FIG. 6 is a top view thereof; and,

FIG. 7 is a bottom view thereof.

The broken lines shown in the drawings represent unclaimed portions of the ice shaver and form no part of the claimed design; the breakaway lines shown in FIGS. 2, 3, 6 & 7 are present for the purpose of ease of illustration.
